7 Claims. (Cl. 51—98)

This invention relates to machines for forming facets in the edges of lenses and more specifically relates to improved mechanism for controlling the positioning of and spacing between such facets.

An object of my invention is to provide a new and improved machine of simple and inexpensive construction and operation for readily and easily forming facets in the peripheral edge portions of lenses.

Another object of my invention is the provision in a facet-grinding machine of improved mechanism for incrementally rotating a lens through a predetermined arc in each cycle of operation during which the lens is shifted toward the grinding tool, is ground and is again shifted away from the grinding tool.

A further object of my invention is to provide in a lens-grinding machine for forming facets in the lens edge, novel mechanism for rotating and selectively controlling the arc of rotation of the lens and the spacing between facets formed by oscillation of the lens toward and away from the grinding tool.

A still further object of my invention is to provide novel and improved manually controllable apparatus for releasably gripping the lens which must be securely held under strong tension during the servicing of the edge portions thereof.

These and other objects and advantages of my invention will more fully appear from the following description made in connection with the accompanying drawings wherein like reference characters refer to similar parts throughout the several views and in which:

Fig. 1 is a top plan view of the machine including the invention;

Fig. 2 is a rear elevation view of the machine shown in Fig. 1;

Fig. 3 is a detail view of a portion of the machine and being taken substantially on a plane as indicated at 3—3 in Fig. 2 and having portions of the background mechanism removed for clarity and simplicity;

Fig. 4 is a detail section view of a portion of the machine with certain portions thereof broken away for simplicity and clarity and taken substantially on a horizontal plane as indicated at 4—4 of Fig. 2;

Fig. 5 is a detail section view with portions of the mechanism broken away and being taken substantially on a vertical plane as indicated at 5—5 of Fig. 1;

Fig. 6 is a detail section view taken on a substantially vertical plane as indicated at 6—6 of Fig. 1; and

Fig. 7 is a plan view of one of the cut spacing wheels with a lens superimposed thereon to show the relation between the spacing of the teeth on the wheel and the spacing of facets on the edge of an irregularly shaped lens.

One form of the invention is shown in the figures and described herein. The machine includes a base plate or frame indicated in general by numeral 10. A source of rotary power comprising motor 11 is affixed on frame 10 adjacent the rear portion thereof. A pair of upright standards 12 are affixed as by bolts 13 to the base 10

and have a rotary shaft 14 journaled in the upper portions thereof. Shaft 14 is keyed to a grinding device or tool 15 for rotation therewith. Shaft 14 has a pulley 16 fixed thereto as by set screws 17 and is connected to the rotary spindle 18 having a pulley 19 secured thereto by means of belt 20. A water receptacle 21 is also carried on standards 12 and has an outlet 22 extending into proximity with the peripheral surface of the rotary grinding tool 15.

Means are provided on the machine for holding a lens L in edge-grinding relation with respect to grinding wheel 15 and for moving the lens toward and away from the wheel 15. In the form shown, such means comprise a tubular handle 23 having a mounting portion 24 which is swingably connected as by pivot 25 to a slide mounting 26. Slide mounting 26 is provided with an opening 27 therethrough through which extends an elongated mounting element or flat bar 28 which is pivotally secured to frame 10 by a bolt 29 and wing nut 30 for swinging movement in a horizontal plane adjacent frame 10. The wing nut 30 may be tightened and loosened to permit the bar 28 to be substantially locked in position on frame 10 and to permit movement thereof about bolt 29. Slide mounting 26 has a manually operable set screw 31 threadably carried therein and disposed for engaging the bar 28 for locking slide mounting 26 in a desired position along the length of bar 28.

A lens holder indicated in general by numeral 32 is carried by handle 23 and the mounting 24 thereof for oscillatory movement with the handle 23 toward and away from the grinding tool 15. In the form shown, the lens holder includes a pair of jaws 33 and 34 which may be provided with suitable padding for engaging the lens surfaces and which are rotatable about an axis extending transversely of and through the lens. Jaw 33 is fixed to a supporting post 35 which is journaled in handle mounting 24. Jaw 34 is journaled in a supporting arm or element 36 which extends transversely of handle 23. Supporting arm 36 is affixed to a sleeve member 37 which is slidably mounted in the hollow interior of handle 23. Support arm 36 is also provided with an annular flange 38 which extends outwardly around sleeve 37 and is coaxially disposed relative to handle 23. A guide rod 39 is threadably affixed at 40 to handle 23 in the interior thereof and has a resiliently yieldable compression spring 41 disposed therearound. The upper end portion of spring 41 engages and bears against suitable stop means such as nut 42 which is threadably secured on the upper end portion of rod 39. The lower end portion of spring 41 engages and bears against the inwardly extending end 37a at the bottom portion of sleeve 37. A closure cap 43 is carried on the upper portion of sleeve 37 for closing the same.

The present invention includes improved means for shifting jaws 33 and 34 away from each other. Such means include an actuating element 44 which has a yoke 45 formed on the inner end thereof which extends around opposite sides of sleeve 37. Yoke 45 bears against the flange 38 and the upper annular edge of handle 23. A pin 46 extends through suitable aligned apertures provided in flange 38, yoke 45 and an appendage portion 23a of handle 23 for securing actuating element 44 in operative position. The outer end portion 47 of actuating element 44 extends generally outwardly from handle 23 and away from the jaws 33 and 34, and the outer portion 47 is flattened and smoothly rounded at the edges so that it may be comfortably engaged and operated by the palm of a person's hand.

The present invention includes drive means for incrementally rotating lens L in synchronism with the oscillatory forward and rearward movement thereof toward and away from grinding wheel 15. Such drive means are

also adjustable for permitting the lens to be selectively rotated through a desired and predetermined arc each time the same is shifted for forming differently spaced facets in the lens edge. Such drive means include a driven mechanism which, in the form shown, comprises a pair of rotary ratchet or driven elements 48 and 49 which are coaxially interconnected and affixed to the rotary supporting post 35. The ratchet elements 48 and 49 are substantially circular and are provided with teeth 50 and 51 respectively which are of different sizes and which are spaced differently around the peripheral edge portions of the ratchet elements. In the form shown, the teeth 50 are spaced farther apart than are teeth 51.

Such drive means also include driving mechanism which comprises, in the form shown, a pair of pawls or driving elements 52 and 53. Pawls 52 and 53 are connected through mounting member 54 and frame 10 to the grinding device 15 for relative oscillatory movement with respect to the driven or ratchet elements 48 and 49 and toward and away from the grinding device 15. Pawls 52 and 53 are swingably mounted for movement about a substantially vertical axis on pin 55 which is fixed in mounting member 54. A pair of coil springs 56 and 57 are carried on pin 55 and respectively bear against pawls 52 and 53 for urging the same into engagement with the teeth of ratchet wheels 48 and 49 respectively. Mounting member 54 is swingably mounted on pivot 25. Means are also provided for restricting the swinging movement of mounting member 54 with respect to frame 10 and in the form shown, such means include a pair of braking washers 58 which are also carried on pivot 25 and which engage the mounting 54. Brake washers 58 may be constructed of any suitable material such as an asbestos fabric with metallic threads interwoven therein. The braking washers 58 are urged into braking engagement with mounting member 54 by washers 59, retaining element 60 and a nut 61 which is threadably secured to the end of pivot 25.

Means are also provided on mounting member 54 for controlling pawls 52 and 53 and for selectively causing the same to engage and disengage their respective ratchet elements 48 and 49. Such means is best seen in Figs. 4 and 5 and includes a control 62 which is rotatably mounted on screw 63 which is threadably affixed to mounting 54. The control 62 is also slidably on screw 63 toward and away from mounting 54, and control 62 is normally resiliently urged inwardly toward mounting member 54 by compression spring 64 which, at one end bears against the inner portion of control 62 and at the outer portion bears against the head of screw 63. A pin 65 is affixed to control 62 and is positioned to extend through either of the apertures 66 and 67 formed in mounting member 54 adjacent the pawls 52 and 53 respectively. As seen in Fig. 4, pin 65 engages pawl 52 when inserted through aperture 66 for shifting pawl 52 out of engagement with the teeth of the ratchet element 48. Similarly, when pin 65 is inserted through aperture 67, pawl 53 is shifted thereby out of engagement with the teeth of ratchet wheel 49.

Means are also provided for controllably limiting the relative oscillatory movement between the driving mechanism and the driven mechanism, that is, between pawls 52 and 53 and ratchet wheels 48 and 49. In the form shown, a pair of stop arms or abutments 68 and 69 are disposed in spaced relation relative to each other and in spaced relation with the post 35 which is affixed to ratchets 48 and 49. In the form shown, arms 68 and 69 are formed integrally of mounting member 54. Arms 68 and 69 along with the mounting portion 24 and mounting member 54, which is mounted on pivot 25 independently of mounting portion 24, provide a yieldable connection between the shiftable lens holder 32 and the driving mechanism which is embodied in the present form of the invention by pawls 52 and 53.

Means are also provided for adjusting the limits of relative oscillatory movement between the driving ele-

ments or pawls 52 and 53 and the driven elements or ratchets 48 and 49. In the form shown, such means include a stop element 70 which is secured by rod 71 to the control 62 for rotary and reciprocating movement therewith. Stop element 70 is positioned inwardly of arm 68 and in engagement with abutment 72 which is affixed to arm 68, when the control 62 is positioned so that pin 65 is inserted through aperture 66 for engaging pawl 52. Stop element 70 may be shifted longitudinally and swung 10 with corresponding shifting of control 62 around abutment 72 and into the dotted position thereof shown in Fig. 3 to permit full and unobstructed movement of post 35 with respect to arms 68 and 69.

A supporting device 73 carried by bracket 74 is mounted 15 on the standard 12 for supporting the edge of the lens L as the same is shifted into engagement with the rotary grinding wheel 15.

It will be noted in Fig. 7 that in order to make the facets formed in the lens L of regular size, the teeth 20 formed in the ratchet element 48 must be irregularly shaped because the ratchet element 48 is circular in shape and whereas the lens L has an irregular peripheral outline. The ratchet teeth in ratchet element 49 are similarly irregularly spaced so as to provide for the regular spacing 25 of facets formed in the peripheral edges.

Operation

In the operation of the lens-grinding machine, the handle 23 will be manually gripped by the ends of the person's 30 fingers and the palm of his hand will be placed upon the upper side of actuating member 44. Although the spring 41 is exceedingly strong, the actuating element 44 may be fulcrumed against the upper portion of handle 23 and the flange 38 so as shift jaw 34 away from jaw 33. The 35 lens L will then be placed between the jaws 33 and 34 in the manner shown in Fig. 6 so that the axis of rotation of the holder 32 will extend transversely of and through the lens. The actuating element 44 will then be released to cause the jaws to securely grip the lens.

The operator of the lens-grinding machine may then 40 shift his grip directly onto handle 23 to permit convenient and easy operation thereof. If it is desired to grind relatively small facets in the lens edges, the control 62 will be placed in the condition shown in full lines in 45 the drawings. The stop element 70 is thereby placed between the abutment 72 and the post 35 for limiting the relative oscillatory movement between the driven or ratchet means and the driving or pawl means, and in addition pin 65 is inserted through the upper aperture 50 66 into engagement with pawl 52 to swing the forward engaging portion thereof out of engagement with the ratchet element 48. Pawl 53 will remain in engagement with the lower ratchet wheel 49 for driving the same and determining the incremental arcs through which lens L 55 will be rotated as the same is shifted toward and away from the grinding device 15.

It may be desirable to move the lens-holding device toward or away from wheel 15 by moving slide mounting 26 along the flat bar 28 and it also may be desirable to swing 60 the holder about the bolt 29 so as to cause the lens when oscillated forwardly about pivot 25 to engage the grinding wheel 15 in a particular manner so as to form facets of desired contours. After the flat bar 28 and the slide mounting 26 have been fixed in position, handle 23 may 65 be oscillated about pivot 25 toward and away from wheel 15 and thereby similarly shift lens L toward grinding wheel 15, into engagement therewith, and away from wheel 15. As handle 23 is oscillated forwardly from the position shown, the lens L and ratchet 49 will be 70 moved forwardly, and during the first incremental forward movement thereof, the mounting member 54 will remain in a stationary position because of the action of the braking washers 58. The ratchet element 49 is shifted forwardly relative to pawl 53 which remains substantially 75 stationary and the pawl 53 will swing slightly about its

pivot 55 and will be urged into engagement with the next tooth 51 disposed clockwise from the tooth previously engaged. As the handle 23 continues to be moved forwardly, arm 69 of mounting frame 54 will be engaged by post 35 so as to cause cooperative movement about pivot 25 of the ratchet 49 and pawl 53 and there will be no more relative movement therebetween during the forward motion of handle 23. Lens L will substantially engage the grinding wheel 15 and a facet will be formed in the edge of the lens. When the facet has been formed, handle 23 will be again swung rearwardly about pivot 25 and because of the action of the braking washer 58 the mounting frame 54 will at least momentarily remain stationary, thereby causing a relative movement between the ratchet element 49 and pawl 53 about pivot 25. Because pawl 53 is engaged with one of the teeth 51 of ratchet 49, the relative oscillatory movement therebetween will be transformed into a rotary movement of ratchet 49 about the axis of rotation thereof to cause the lens holder 32 to rotate through an increment proportional to the spacing of one of the teeth 51 of ratchet 49. The rotation of ratchet 49 and holder 32 is limited by the limits of oscillatory movement permissible between ratchet 49 and pawl 53 and this is defined by the spacing between stop element 70 and arm 69. When the post 35 engages stop element 70 the mounting frame 54 and pawl 53 will swing, along with handle 23 and ratchet 49, about pivot 25, rearwardly away from grinding wheel 15. The lens L will have then been rotated through an arc and will be properly positioned for engagement with the grinding wheel 15 again so that a properly positioned facet away may again be formed therein adjacent the previously formed facet.

The described cycle of operation will be repeated and the handle 23 will be moved forwardly and the pawl 53 will move to the next adjacent tooth 52 in ratchet 49.

Handle 23 will be oscillated forwardly and rearwardly about pivot 25 to cause the lens L to engage the grinding wheel 15 a multiplicity of times until facets have been formed all the way around the peripheral edge of the lens. Depending upon the design of the lens desired, the lens 40 may thereafter be turned over so as to form facets adjacent the bottom surface in the peripheral edge thereof.

If it is desired to form facets of a somewhat larger size in the lens edges, the control 62 will be pulled outwardly from mounting frame 54 so as to retract pin 65 from aperture 66 and so as to retract stop element 70 away from abutment 72. The control 62 will be rotated so as to insert pin 65 into aperture 67 and so as to swing the stop element 70 into the dotted position thereof shown in Fig. 3. When the pin 65 is removed from aperture 66, pawl 52 will be resiliently urged by spring 56 into driving engagement with the teeth 50 of ratchet 48. The pawl 52 and the spacing between teeth 50 will thereupon control and be determinant of the spacing between the facets formed in the lens L. When pin 66 is inserted into aperture 67, pawl 53 will be swung around pivot 55 out of engagement with the ratchet 49, and in addition the stop element 70 is removed from between abutment 72 and post 35. The operation of the mechanism is substantially similar to that already described with the exception that there will be slightly greater relative oscillatory movement between ratchet 48 and pawl 52 than was permissible between ratchet 49 and pawl 53. This is necessary to permit the relatively greater shifting due to the larger teeth 50.

It will be seen that I have provided an improved and novel mechanism in a lens facet-grinding machine for controllably producing relative rotation between the lens to be ground and the grinding device each time the lens is successively brought to bear against and shifted away from the grinding device and forming facets of desired size and spacing in the lens.

It should also be noted that I have provided novel and improved mechanism for readily and easily shifting the lens-gripping jaws away from each other to facilitate the

insertion of a lens therebetween even though the spring pressure on the jaws may be very considerable, and wherein said mechanism is provided with an actuating element disposed so that substantial force may be applied thereupon with the palm of the hand and so that it will normally be out of the way when the lens-grinding machine is used in its conventional manner.

It will, of course, be understood that various changes may be made in the form, details, arrangement and proportions of the parts without departing from the scope of my invention which consists of the matter shown and described herein and set forth in the appended claims.

I claim:

1. Apparatus for grinding facets in lens edges, comprising a frame, a grinding device mounted on said frame, a releasable lens-holding device shiftably mounted on said frame for oscillatory movement toward and away from said grinding device, said holding device being constructed and arranged for holding a lens in edge-grinding relation relative to said grinding device, said lens-holding device also being rotatable about an axis extending transversely of and through the lens, a rotary ratchet element secured to said holding device for movement therewith, a mounting member mounted on said frame adjacent said ratchet element for restricted oscillatory movement toward and away from said grinding device, a pawl movably mounted on said mounting member and engaging said ratchet element in driving relation, said pawl and said ratchet element being relatively movable for power transmission therebetween, and cooperatively abutting stop elements on said holding device and said mounting member and limiting the magnitude of movement therebetween for limiting rotative movement of said pawl and ratchet element, whereby to progressively and incrementally rotate the lens as the same is shifted toward and away from said grinding device and thereby form spaced facets in the peripheral edge thereof.

2. Apparatus for grinding facets in lens edges, comprising a frame, a grinding device, a lens-holding device, said devices mounted on said frame for relative oscillatory movement toward and away from each other into and out of lens-grinding relation, said holding device being arranged to position the lens in edge-grinding relation relative to the grinding device, said devices also being rotatable relative to each other about an axis extending transversely of and through the lens, adjustable drive means operatively connected with said devices and including a rotary driven mechanism and a driving mechanism each drivably engaging the other and each drivably connected with a respective device to be operated with relative oscillatory movement of said devices, said mechanisms being movable relative to each other for power transmission therebetween and said mechanisms being constructed and arranged for producing relative rotation of said devices when operated by relative oscillatory movement of said devices, adjustable movement-limiting means connected with said frame and being operatively connected with said driven mechanism and said driving mechanism, said limiting means being constructed and arranged for selectively and adjustably limiting the magnitude of relative movement of said driven mechanism and said driving mechanism, whereby to controllably vary the incremental relative rotation of said devices as the same are shifted toward and away from each other and thereby vary the spacing of facets formed in the lens edge.

3. Apparatus for grinding facets in lens edges, comprising a frame, a grinding device mounted on said frame, a lens-holding device mounted on said frame, one of said devices being shiftable toward and away from the other of said devices, said holding device being constructed and arranged to hold the lens in edge-grinding relation relative to the grinding device, one of said devices being rotatable relative to the other of said devices about an axis extending transversely of and through the lens, a rotary

driven mechanism drivably connected with said rotatable device for rotating the same, driving mechanism drivably connected with said rotary driven mechanism for rotating the same, a yieldable connection between said shiftable device and said driving mechanism, adjustable movement-limiting means operatively connected with said driving mechanism and with said driven mechanism and being constructed and arranged for adjustably and selectively limiting the magnitude of relative movement of said driving mechanism and said driven mechanism, whereby to adjustably vary the incremental rotary movement of said rotatable device and thereby vary the spacing of facets formed in the lens edge.

4. Apparatus for grinding facets in lens edges, comprising a frame, a grinding tool mounted on said frame, a lens holder shiftably mounted on said frame for oscillatory movement toward and away from the grinding tool, said holder being arranged for positioning the lens in edge-grinding relation relative to said grinding tool, said holder also being rotatable on an axis extending transversely of and through the lens, a rotary driven mechanism drivably connected with said lens holder and being shiftably mounted for oscillatory movement therewith, driving mechanism shiftably mounted on said frame for movement toward and away from the grinding tool and being shiftable relative to said driven mechanism, said driving mechanism drivably engaging the driven mechanism and being constructed and arranged for rotating the same when shifted relative thereto, adjustable stop means operatively connected between said driven mechanism and said driving mechanism and being constructed and arranged for adjustably limiting the magnitude of relative movement between said driven mechanism and said driving mechanism, whereby to incrementally rotate said holder and the lens as the same are shifted toward and away from the grinding tool for spacing the facets formed at desirable intervals in the lens edge.

5. Apparatus for grinding facets in lens edges, comprising a frame, a grinding tool mounted on said frame, a lens holder shiftably mounted on said frame for oscillatory movement toward and away from said grinding tool, said lens holder being arranged to position the lens in edge-grinding relation relative to the grinding tool, said lens holder also being rotatable about an axis extending transversely of and through the lens, at least a pair of rotary and substantially circular drive elements drivably connected with the lens holder and being movably carried by said frame for oscillatory movement with the lens holder, said drive elements having spaced driving teeth on the periphery, the spacing between said teeth on one of said drive elements being different than the spacing between the teeth on the other of said drive elements, a mounting member adjustably mounted on said frame for oscillatory movement relative to said drive elements and toward and away from the grinding tool, pawl means movably mounted on said mounting member and being constructed and arranged for selective and interchangeable driving engagement with said drive elements and the differently spaced teeth thereof, stop means operatively connected between said drive elements and said pawl means and being constructed and arranged for restricting the magnitude of relative movement thereof, whereby to selectively vary the incremental arc of rotation of said holder and the lens when the same are shifted toward and away from the grinding tool and thereby selectively vary the spacing of facets formed in the lens edge.

6. Apparatus for grinding facets in lens edges, comprising a frame, a grinding tool mounted on said frame, a lens holder shiftably mounted on said frame for oscillatory movement toward and away from said grinding tool, 5 said lens holder being arranged to position the lens in edge-grinding relation relative to the grinding tool, said lens holder also being rotatable about an axis extending transversely of and through the lens, at least a pair of rotary and substantially circular drive elements drivably 10 connected with the lens holder and being movably carried by said frame for oscillatory movement with the lens holder, said drive elements having spaced driving teeth on the periphery thereof, the spacing between said teeth on one of said drive elements being different than the spacing between the teeth on the other of said drive elements, 15 a mounting member adjustably mounted on said frame for oscillatory movement relative to said drive elements and toward and away from the grinding tool, adjustable pawl means movably mounted on said mounting member and being constructed and arranged for selective and interchangeable driving engagement with said drive elements and the differently spaced teeth thereof, adjustable stop means operatively connected between said drive elements and said pawl means and being constructed 20 and arranged for limiting and varying the magnitude of relative movement thereof, and a control connected with said stop means and with said pawl means for simultaneously adjusting the same to change the relative movement between said pawl means and said drive elements 25 when said pawl means change from driving engagement with one driving element to driving engagement with the other of said drive elements.

7. Apparatus for grinding facets in lens edges, comprising a frame, a grinding tool mounted on said frame, 30 a lens holder shiftably mounted on said frame for oscillatory movement toward and away from the grinding tool, said lens holder being arranged to position the lens in edge-grinding relation relative to the grinding device and said lens holder also being rotatable about an axis extending transversely of and through the lens, at least a pair of rotary and substantially circular drive elements drivably connected with said lens holder and being movably carried on said frame for oscillatory movement with the holder toward and away from the grinding tool, said drive elements having spaced driving teeth on the periphery thereof, said teeth on one of said drive elements being spaced differently than the teeth on the other of said driving elements, a mounting member shiftably 40 mounted on said frame for oscillatory movement relative to said drive elements and toward and away from the grinding tool, a pair of movable ratcheting pawls each mounted on said mounting member adjacent a respective drive element for movement toward and away therefrom, 45 shiftable control means mounted on said mounting member and being operatively connected with said pawls for selectively and interchangeably moving the same into and out of driving relation with the respective driving elements, and stop means operatively connected between 50 said pawls and said drive elements for limiting relative oscillatory movement thereof, whereby to selectively vary the spacing of facets formed in the lens edge.
